United States Patent Office.

WILLIAM E. HARDIN, OF BOWLING GREEN, MISSOURI.

Letters Patent No. 67,756, dated August 13, 1867.

IMPROVEMENT IN PLOUGHS.

The Schedule referred to in these Letters Patent and making part of the same.

TO ALL WHOM IT MAY CONCERN:

Be it known that I, W. E. HARDIN, of Bowling Green, in the county of Perry, and State of Missouri, have invented a new and useful Improvement in Ploughs; and I do hereby declare that the following is a full and clear description thereof, reference being had to the accompanying drawings and to the letters of reference marked thereon.

This invention relates to the employment of a wheel or roller under the heel of the plough, the exterior face of the said wheel or roller being arranged to coincide with the vertical plane in which the land-side of the plough is located, the metal plate which forms the land-side in the old construction of ploughs being omitted in this, to give room for the wheel.

The object of the invention is to lessen the draught of the plough, by producing rolling friction instead of sliding, as is the case where the land-side is formed of a straight plate of metal.

To enable those skilled in the art to make and use my improved plough, I will proceed to describe its construction and operation.

Figure 1, of the drawings, is a side elevation of the improved plough, and

Figure 2 is a rear end elevation of it.

The plough A B may be of any approved form or pattern, with the exception of the land-side, which is omitted in the present instance, so as to allow room for the wheel or roller C, the said wheel or roller in reality forming the land-side of the plough. This wheel C is attached to a shaft, C', which has its bearings in the lower end of the handle-piece or post a, and in the piece a' attached to the mould-board, as is clearly shown in fig. 2: The bearing at a' may be formed by means of a screw-pivot point, so as to allow a ready means of adjustment of the parts. The exterior face of the wheel C may be formed either with or without a flange, c, on the periphery, and the said face of the wheel may be either flat or convex.

The object of the wheel C, employed as above described, is to reduce the friction to a minimum, by producing rolling instead of sliding friction. Ploughs constructed in this manner are more easily handled in turning than those with straight land-sides.

Having described my invention, what I claim is—

The wheel C, when combined with a plough, A B, in the manner and for the purpose set forth.
